UNITED STATES PATENT OFFICE

JANNE FREDRIK LJUNDAHL, OF STOCKHOLM, SWEDEN

POTATO-SETTING MACHINE

Application filed November 25, 1929. Serial No. 409,699.

The present invention refers to a machine for setting potatoes and to a machine of the type wherein the potatoes from a suitable storage receptacle are fed into drop tubes 5 or the like provided with dampers, at the opening of which the potatoes drop down on conveying means provided with needle-shaped projections for piercing the individual potatoes, such conveying means being 10 intermittently movable so that the conveying member for each drop tube is at rest in a position so that a needle-shaped projection, or a group thereof, is located beneath the lower open end of each drop tube when the damper 15 therein is opened. Thereby the potato is caught by the needle, or group thereof, as thereafter by the movement of the conveying means to be transmitted to a setting tube, in which the potato is removed from the needle, 20 or needle group, so that the same is dropped down into the setting furrow by the intermediary of the setting tube.

As the interdistance between the separate potatoes in said furrow shall be uniform and 25 constant, it is clear that the frequency of movement of the damper and the intermittently movable conveying means is dependent of the driving speed of the setting machine. When using one single setting device for 30 each furrow, the driving speed of the machine must be very low only, as the time required for opening and closing of the damper would be insufficient, and the potato dropping down on the damper would not have 35 sufficient time for taking a position of rest before the opening of said damper. Therefore the machine is provided with two or more complete setting devices for each furrow to be set, and each of said devices is provided 40 with a drop tube or the like having the necessary damper, and a corresponding needle-carrying conveyor means, and thereby the dampers and conveying means, which suitably transmit the potatoes to one single 45 setting chute, are adapted to be alternately set into action at the driving of the machine. In this manner the driving speed may be increased two times or more, and the machine will nevertheless perform the setting in an 50 even and uniform manner involving sufficient

time for the opening and closing of the dampers and for permitting the separate potatoes to take a position of rest before being fed out, whereby the dropping height of the potatoes can be chosen so large that they will 55 be properly affixed to the needle points before being conveyed further.

The setting tubes alternately delivering the potatoes to the same furrow, which tubes are suitably combined with one single setting 60 chute finally conveying the potatoes to their places in the furrow, are each provided with a damper, and such dampers are connected with the dampers provided in the drop tubes in such a manner, that a drop damper belonging to one of the setting devices is opened simultaneously with the setting damper belonging to the other setting device, and vice versa. Hereby it is secured that the setting 65 of the potatoes in the furrow takes place alternately from each of the two setting devices in a completely uniform manner, so that the potatoes are set in the furrow in equally interspaced relation throughout.

An embodiment of the invention is described in the following by reference to the accompanying drawing, in which

Fig. 1 shows the parts of the machine needed for an explanation of the invention and seen in elevation partly in section.

Fig. 2 shows the same machine parts seen from the front side of the machine.

In the drawing, 1 represents the framing of the machine, such framing being supported by wheels 2, and a suitable driving transmission being mounted between said wheels and the setting devices nearer described in the following.

The framing 1 serves as a support for a container 3 from which the potatoes are fed out by means of bucket elevators 4, each discharging the potatoes into a drop tube 5. For each furrow to be set there are provided two drop tubes 5 each combined with a setting tube 6, and both of the setting tubes discharge into a common setting chute 6^a conveying the potatoes from both of the setting devices into the same furrow, which is ploughed up and filled again by suitable 90 95 100

shares or bills (not shown) in the common manner.

In each dropping tube there is provided a damper 7, and the dampers in the coacting drop tubes are each mounted on a shaft 8 and 9 respectively, such shafts by means of links being each connected with an arm 10 and 11 respectively rockably mounted on a fixed part 12 of the framing. The arms 10, 11 are interdistantly positioned in the path of travel of pins 13 mounted on a wheel 14, so that said arms are alternately acted upon by the said pins at the rotation of the wheel 14 which is continuously rotated at the driving of the machine by means of a suitable transmission from the shaft of the wheels 2.

The wheel 14 serves for the intermittent driving of a wheel 15 on a shaft 16 which beneath each drop tube 5 carries a sprocket wheel 17, and around this wheel and a wheel 18 is mounted a chain 19 provided with a number of needles or needle groups 20. The wheels 14 and 15 are provided with coacting cam discs by means of which the wheel 15 is kept fixed during its periods of rest. The construction is of such a kind that, when each chain is at rest, a needle or group thereof 20 is in a central position beneath the corresponding drop tube, when the damper 7 therein is opened, so that the potato then dropping is fixed to the upwardly pointing needle or needle group 20. Further the construction is of such a kind that the aforesaid manner of action takes place alternately at the one or other of the coacting drop tubes, and that the potatoes emanating from both of the drop tubes are conveyed alternately by means of the chains 19 against whipping plates 21 serving the purpose of whipping off the potatoes from the needle groups into the corresponding setting tube 6. Only one potato can at a time be affixed to the needle group at hand beneath the corresponding drop tube, and in case more potatoes should have entered the drop tube simultaneously, the rest of them will drop down into a collecting tray 22 which may be emptied into the container 3 when desired.

The setting tubes 6 are provided with dampers 23 mounted each on a shaft 24 and 25 respectively, such shafts being provided with crank levers connected with links 26 and 27 respectively, and these links are coupled to the links 9' and 8' respectively for the dampers 7, so that the damper 23 in the right hand setting device is opened simultaneously with the damper 7 in the left hand one, and vice versa. By this arrangement it is obtained that the potatoes are set uniformly and equidistantly in the furrow by means of the alternately functioning setting devices, even if the machine is driven at a great speed.

Hereby it is of a certain importance that the conveying of the potatoes from the drop tubes 5 to the setting tubes 6 is performed by means of conveying chains 19 instead of by simple wheels provided with needles, as previously proposed, as in such latter case the potatoes affixed to the needles are subjected to a strong centrifugal action at the intermittent rotation of the wheel, so that they would often be loose too soon and be thrown about in an uncontrollable manner. By conveying the potatoes by means of the conveyor chains 19 described above, the potatoes will not be subjected to any centrifugal action until the direction of travel of the chain is reversed around the wheel 18, and at that point the potatoes shall actually be removed from the conveyor chain or from the group of needles thereon. On account of the arrangement of the dampers 23 it is thereby of no consequence if the loosening of the potatoes takes place a little sooner or later during the periods of movement of the chains, as the potatoes due to said dampers will nevertheless not be delivered into the furrow until due therefore, and therefore the uniform interdistance between the potatoes set in the furrow will be secured.

It is obvious to anyone skilled in the art that the machine may be constructed for the simultaneous setting of two or more furrows, and for each furrow the machine is to be provided with two combined setting devices adapted for an alternate functioning in the manner described above. The constructional particulars, especially for the interconnection of the dampers, may of course be varied within rather great limits without departing from the principle of invention, and the invention is not limited to the particulars described above for the sake of explanation.

What I claim and desire to secure by Letters Patent is:—

1. A potato setting machine comprising a container for the potatoes to be set, two drop tubes for each furrow, means for conveying the potatoes from said container into the drop tubes, a drop damper in each drop tube, an intermittently movable conveyor means positioned beneath the lower open end of each drop tube, driving means for both of the conveyors and adapted for driving them alternately, a setting tube positioned at the discharge end of each conveyor, a setting damper in each setting tube, a common setting chute leading from the discharge ends of both setting tubes into the furrow to be set, driving means for opening and closing of all of the dampers, and interconnection means between said dampers adapted for performing an opening and closing of the drop damper belonging to one of the setting devices simultaneously with the opening and closing of the setting damper belonging to the other setting device, and vice versa.

2. A potato setting machine as stated in
claim 1, comprising the additional feature
that the conveyor means belonging to each
setting device consists of an endless chain
member running on more than one wheel and
provided with needle means for affixing the
potatoes dropping down thereupon.

In testimony whereof I have signed my
name to this specification.
